US0D1040999S

(12) United States Design Patent (10) Patent No.: US D1,040,999 S
(45) Date of Patent: * Sep. 3, 2024

(54) SLIM-FIT MASK

(71) Applicant: Brilliant Medical Corporation Limited, Hong Kong (CN)

(72) Inventor: Yuen Yan Lai, Hong Kong (CN)

(73) Assignee: BRILLIANT MEDICAL CORPORATION LIMITED, Hong Kong (HK)

() Term: 15 Years

(21) Appl. No.: 29/779,552

(22) Filed: Apr. 20, 2021

(51) LOC (14) Cl. 29-02

(52) U.S. Cl.

USPC D24/110.1

(58) Field of Classification Search
